(57) **CLAIM**

The ornamental design for a display system or portion thereof with graphical user interface, as shown and described.

DESCRIPTION

The sole FIGURE is a front view of a display system or portion thereof with graphical user interface showing our new design.

The outermost broken lines show the field of view for a visual display and form no part of the claimed design. The dot-dash broken lines indicates a boundary of the claimed design. The appearance of any portion of the graphical user interface outside the boundary forms no part of the claimed design. Color forms no part of the claimed design.
